UNITED STATES PATENT OFFICE.

LOUIS J. MESSIER AND EUCLID J. MERCURE, OF PITTSFIELD, MASSACHUSETTS.

LETTER-BOX.

SPECIFICATION forming part of Letters Patent No. 651,576, dated June 12, 1900.

Application filed August 21, 1899. Serial No. 727,950. (No model.)

To all whom it may concern:

Be it known that we, LOUIS J. MESSIER and EUCLID J. MERCURE, citizens of the United States, residing at Pittsfield, in the county of 5 Berkshire and State of Massachusetts, have invented certain new and useful Improvements in Letter-Boxes, of which the following is a specification.

This invention relates to certain new and 10 useful improvements in letter-boxes; and it has for its object, among others, to provide a simple and cheap device of this character so constructed that the mail may be deposited in the box with a single movement of one hand 15 and not requiring the use of two hands, as heretofore. We provide a double closure, a door, and a cap so connected that the movement of the one actuates the other. Means are provided for guiding the mail toward the 20 front of the box, where it can be easily gotten at by the postman, and means are also provided for preventing the letters from getting back of the guiding means. Further means 25 are provided for guarding against the ingress of rain or snow, and the device as a whole is capable of manufacture at small cost, yet is durable and most efficient for the purposes for which it is intended.

Other objects and advantages of the invention 30 will hereinafter appear, and the novel features thereof will be specifically defined by the appended claim.

The invention is clearly illustrated in the 35 accompanying drawings, which, with the letters of reference marked thereon, form a part of this specification, and in which—

Figure 1 is a front elevation of a letter-box 40 constructed in accordance with the invention. Fig. 2 is a vertical section through the same

Like letters of reference indicate like parts in the different views.

Referring now to the details of the drawings by letter, A designates the box proper, 45 which may be of any suitable material, shape, and capacity. In this instance it is shown as substantially rectangular with a rounded top a, this being the conventional form; but such shape is not material.

B is the door through which access is had to the interior of the box to remove the mail-

matter therein. It is hinged at the bottom, as at b, and is provided with the side pieces B', as usual, which move within the space between the sides of the box. At the upper 55 edge this door is offset or rabbeted, as seen at b' in Fig. 2, to engage a corresponding offset or rabbet to form a water-tight joint. The front of the box is provided with the inclined ledge or shelf C at a point in proximity to this 60 joint, as shown, and is designed for the purpose of shedding the water or snow, as will be readily understood. The side pieces B' at their inner ends are provided with the projection or shoulder D, which serves as a stop to 65 limit the outward movement of the door.

E is a plate in the back of the box, designed to guide the mail toward the front. It is hinged, as at e, and on the back wall of the box in proximity to this hinge is a projection 70 or inwardly and downwardly inclined flange F, (seen clearly in Fig. 2,) which serves to prevent a letter from getting caught behind the upper end of the said plate or slide.

In the front wall of the box are two openings, or, rather, one opening having two closures.

G is a door designed to close the lower portion of the opening, and H is a cap for closing the upper portion thereof. The top and 80 bottom edges of the door and cap are inclined, as seen in Fig. 2, and make a tight fit, yet allow of easy movement of the door and cap when desired. The cap is provided at its lower edge with a projecting flange or ledge 85 h, which serves to shed the water from the joint between the door and cap, while on the front wall of the box, above the top edge of the cap, is another projection or ledge i, which serves a similar function in connection with 90 the joint between the upper edge of the cap and the opening in the wall of the box.

The door G is carried by levers I, one at each side of the box, pivotally mounted between their ends upon pivots I', projecting 95 from the opposite sides of the box. The lower ends of the levers I are pivotally connected, as at j, with links J, the inner ends of which are pivotally connected to plates K, one at either side of the box, supported upon pivots 100 L, projecting from the sides of the box. These plates K, which are of semicircular

form, are secured to or formed integral with the cap H.

By pushing inward upon the door G the cap H is tilted inward through the medium of the levers I, links J, and plates K, thus exposing an opening through which the letter is dropped.

What is claimed as new is—

10 with a transverse opening at its front, of a double closure for said opening, comprising a door closing the lower portion of said opening: and a cap closing the upper portion of the opening: arms projecting from the door

and pivotally secured to the sides of the box: 15 plates also pivotally secured to the sides of the box and having link connections with said arms: said plates and cap counterbalancing the door, and said cap having an edge flange overlapping the upper edge of the door. 20

In testimony whereof we affix our signatures in presence of two witnesses.

LOUIS J. MESSIER.
EUCLID J. MERCURE.
